UNITED STATES PATENT OFFICE.

HARRY B. HILLS, OF RIVERTON, NEW JERSEY, ASSIGNOR TO STEWARD DAVIT & EQUIPMENT CORPORATION, OF NEW YORK, N. Y., A CORPORATION OF NEW YORK.

BOAT-DETACHING APPARATUS.

1,287,994.

Specification of Letters Patent. Patented Dec. 17, 1918.

Application filed October 1, 1918. Serial No. 256,375.

To all whom it may concern:

Be it known that I, HARRY B. HILLS, a citizen of the United States of America, residing in Riverton, in the county of Burlington, in the State of New Jersey, have invented certain new and useful Improvements in Boat-Detaching Apparatus, of which the following is a true and exact description, reference being had to the accompanying drawings, which form a part thereof.

My invention relates to boat davit apparatus such as is used for launching life boats from ships and particularly to such apparatus as is provided with locking and unlocking devices for holding the mechanism, which couples the boat at bow and stern to the davit tackle in engaged position and releasing it when desired.

The object of my invention is to provide such apparatus with a supplemental locking device actuated by the weight of the stern of the suspended boat only, and whereby the locking devices which couple the boat to the davit tackle are held in engaged position until the stern of the boat is supported by the water, and my invention consists, generally speaking, in providing, for boat davit apparatus of the kind referred to, a supplemental locking device operatively actuated by the weight of the stern of the suspended boat only and acting to prevent the disengagement of the boat from the davit tackle at all times, except when the stern of the boat is water borne, and to permit its ready disengagement at all times when the stern of the boat is water borne.

Reference being now had to the drawing which illustrates my invention in what I believe to be its most simple and efficient embodiment and in which:

Figure 1 is a longitudinal vertical section of a boat provided with my improved locking device.

Fig. 2 is an enlarged view showing a device for attaching the boat's stern to the falls with releasing mechanism, and a supplemental locking device operatively actuated by the weight of the stern of the boat.

Fig. 3 is a view similar to Fig. 2, but showing a modified form of supplemental locking device, and

Fig. 4 is a view showing a device for attaching the bow of the boat to the falls.

A is the boat, A' its bow, and A² its stern, B and B' are the falls by which the boat is

suspended from the davits, B² B² being eyes with which the hooks on the boat engage, C and C' are the engaging devices secured to the bow and stern of the boat, and, as shown, they and the mechanism for locking and releasing them are generally the same as shown and described in my application for Letters Patent filed June 23, 1917, Serial No. 176,477. The device, as shown, consists of a channel iron D having outwardly extending parallel flanges D' in which are formed parallel slots D² for the guidance of the hook locking device or pin G. E is a pivot pin secured to the flanges D' and serving to pivotally support the hook F, which is formed with a locking tail or arm F', which, when the hook is in engaging position extends down alongside of the slots D² and is engaged and locked by the sliding lock G, the retraction of which permits the hook to turn up and release the boat from the falls. As shown, the lock G is actuated by the connecting rod H, crank connected at H' to a rock shaft H² along the bottom of the boat H³ indicating the position of a crank arm for turning the shaft.

All the above described features are found in my former application in which the boat can be released from the falls by withdrawing the locking devices whether the boat is water borne or not, and many other devices are well known which have the same capacity. In my new construction I form the bow engaging device as heretofore with, so far as its own peculiar construction is concerned, the same capacity to be released irrespective of the support of the boat by the water. Thus, as shown, I form the lock contacting face F² of the hook tail straight, so as to offer only frictional resistance to the movement of the lock G. In the stern engaging device, however, I provide a locking device to engage and hold the lock G against retraction, which locking device is operatively actuated by the weight of the stern of the boat, so that until the stern is water supported the locking device will prevent the retraction of the lock, and a very efficient and simple locking device of this kind consists in forming on the locking tail of the hook a projecting finger F³, which projects beneath the lock G and only permits of its withdrawal by a backward movement of the hook tail F' and an actual raising of the boat's stern.

In the construction shown, and this should be true of any embodiment of my invention, the hook locking devices G G at bow and stern are actuated together, being operatively connected by the rock shaft H² and its lock actuating connections; but it will be obvious that the operation of the supplemental locking device at the stern will permit the release of the boat from the falls only when the stern is water borne and irrespective of the position of the bow with respect to the water.

In Fig. 3 I have shown a modified supplemental locking device consisting of a detent 15 D³ formed at the head of the slots D² and used with a straight face F² of the locking tail. Obviously this will operate in the same way as the device of Fig. 2.

My invention is capable of application in

many forms, and these illustrated are simply 20 given by me as the best forms known to me and my claim is not to be understood as limited to the specific devices illustrated.

Having now described my invention, what I claim as new and desire to secure by Let- 25 ters Patent, is:

Davit connections adapted to be secured to the stem and stern of a boat comprising boat engaging and releasing devices in combination with means for locking and releasing 30 said devices simultaneously, and means operatively actuated by the weight of the stern of the boat only whereby the operation of the unlocking means is obstructed while and only while the boat stern is unsupported by 35 the water.

HARRY B. HILLS.
